(57) **CLAIM**

The ornamental design for a therapeutic device, as shown and described.

DESCRIPTION

FIG. 1 is a front top perspective view of a therapeutic device showing the new design;

FIG. 2 is a back bottom perspective view thereof;

FIG. 3 is a front elevation view thereof;

FIG. 4 is a back elevation view thereof;

FIG. 5 is a top view thereof;

FIG. 6 is a bottom view thereof;

FIG. 7 is a left elevation view thereof; and,

FIG. 8 is a right elevation view thereof.

The broken lines in the drawings depict portions of the therapeutic device that form no part of the claimed design.
